ABSTRACT OF THE DISCLOSURE

This disclosure describes a multistep process for recovering a prostaglandin enriched isolate from the cortex of the sea coral *Plexaura homomalla*.

BRIEF SUMMARY OF THE INVENTION

This invention relates to a method of recovering a prostaglandin enriched isolate consisting essentially of prostaglandin A₂ 15-O-acetyl methyl ester, 15-epi-prostaglandin A₂ 15-O-acetyl methyl ester, prostaglandin A₂ methyl ester and 15-epi-prostaglandin A₂ methyl ester from the cortex of the gorgonid *Plexaura homomalla*. More particularly, this invention involves the partition of the material obtained by hexane extraction of dried, comminuted cortex of *Plexaura homomalla*, after removal of solvent, between two immiscible solvent systems. One phase consists of a nitroalkane solvent system selected from the group consisting of nitroalkanes having one or two carbon atoms, and mixtures thereof. The other phase consists of a nitroalkane-immiscible solvent system selected from the group consisting of alkanes having from six to eight carbon atoms, cycloalkanes having from five to seven carbon atoms, and mixtures thereof. Undesired impurities are concentrated in the nitroalkane-immiscible solvent system whereas the desired prostaglandin A₂ derivatives are found in the nitroalkane solvent system and may be recovered therefrom by removal of solvent.

DETAILED DESCRIPTION OF THE INVENTION

The prostaglandins are an important group of substances playing a significant, although as yet not fully defined role in many areas of human biochemistry and physiology. The value of certain prostaglandins, in particular prostaglandin E₂ and prostaglandin F_{2a}, for the induction of labor and as abortifacients has been demonstrated in humans and is under active clinical study. In limited experiments with humans, with and without a history of bronchial asthma, prostaglandin E₁ has been shown to be a potent bronchodilator.

Thus, an inexpensive and convenient source of supply for relatively large amounts of the various prostaglandins is of great importance. The cortex of the sea coral *Plexaura homomalla* contains relatively large amounts of either prostaglandin A₂ 15(S)-O-acetyl methyl ester or the corresponding compound in the 15(R) configuration, or both. Depending upon how the collected samples are handled, there may also be present prostaglandin A₂ methyl ester and its 15-epi isomer as well as the prostaglandin A₂ carboxylic acids. The gorgonid *Plexaura homomalla* is by far the richest source of prostaglandins yet reported. Furthermore, the transformation of the prostaglandin A₂ derivatives of either the 15(S) or 15(R) configuration to 15(S)-prostaglandins E₂ and F_{2a} has been reported as has the transformation of prostaglandin E₂ to prostaglandin E₁ and thence to prostaglandin F_{1a}.

Although the cortex of *Plexaura homomalla* is relatively rich in prostaglandins, the prostaglandin content is nevertheless only about 1-2% of the total. The chemical literature describes column chromatography procedures for the final purification of the prostaglandins following

2

an initial extraction of the cortex with hexane. The starting material for this initial extraction is the outer sheath or cortex of the animal which is peeled or stripped off. The cortex is then comminuted by grinding or by mincing in the usual manner. Also, the fresh cortex may be frozen and then ground to prevent any possibility of loss of prostaglandin content. The comminuted cortex is then dried by any convenient means such as by air-drying on trays in sunshine or by drying in low temperature ovens.

10 If the dried comminuted cortex must be stored for any considerable period of time, it is preferable to store it under nitrogen in order to avoid oxidation of the prostaglandin content thereof.

The initial hexane extraction of the dried comminuted cortex may be carried out with any hexane such as n-hexane, isohexane, 3-methylpentane, 2-ethylbutane, 2,3-dimethylbutane, etc., or with various mixtures of these isomeric hexanes. Best results are obtained when 3-5 liters of isomeric hexanes are employed per kilogram of cortex. The extraction may be carried out at from about 0° C. to about 60° C., preferably at ambient temperature and with agitation, over a period of time of 2-24 hours. The hexane extract is then separated from the insoluble solid residue by any convenient means such as filtration or centrifugation. The solvent is then removed from the hexane extract by evaporation, distillation under vacuum, or freeze drying to provide an initial prostaglandin-containing material. This initial hexane extraction enriches the prostaglandin content of initial prostaglandin-containing material to about 10% from the original 1-2% of the cortex.

The present invention comprises a novel useful, and convenient process for the further enrichment of the prostaglandin content of the initial hexane extract to about 40-60%, thus substantially reducing the complexity, amount of adsorbent, solvent volume, and time necessary for the final chromatographic purification. In the preparation of relatively large quantities of prostaglandins from the cortex of *Plexaura homomalla*, these improvements substantially reduce the economic cost. More particularly, the present invention involves the partition of the material obtained by hexane extraction between two immiscible solvent systems. The first phase consists of a nitroalkane solvent system selected from the group consisting of nitroalkane having one or two carbon atoms, and mixtures thereof. The second phase consists of a nitroalkane-immiscible solvent system selected from the group consisting of alkanes having from six to eight carbon atoms, cycloalkanes having from five to seven carbon atoms, and mixtures thereof. Suitable second phase solvent systems are, for example, a mixture of isomeric hexanes, a mixture of isomeric heptanes, a mixture of isomeric octanes, cyclopentane, cyclohexane, cycloheptane, a 1:1 by volume mixture of isomeric hexanes and isomeric octanes, a 1:1 by volume mixture of cyclopentane and isomeric hexanes, and the like.

The partition of the ca. 10% prostaglandin-containing material is best carried out with about equal volumes of first and second phase solvent systems, although considerable variation is permissible with this parameter. Preferably, about 3-5 liters sum total of the solvent phases is employed per kilogram of the hexane extract material. Partition is carried out, with agitation, at a temperature of from about 0° C. to about 60° C., preferably at ambient temperature, over a period of time of 2 minutes to one hour. Thereupon, the nitroalkane-immiscible second phase solvent system is separated and discarded. Solvent is then removed from the nitroalkane first phase solvent system by evaporation, vacuum distillation, or freeze drying to provide a prostaglandin enriched material containing about 40-60% of prostaglandins. The 15(S) and/or

15(R) prostaglandin A₂ 15-O-acetyl methyl esters, as well as the corresponding prostaglandin A₂ methyl esters, and sometimes the corresponding prostaglandin A₂ carboxylic acids, are found in this final concentrate and may be subsequently isolated and purified by column chromatography.

The invention will be described in greater detail in conjunction with the following specific example.

EXAMPLE 1

Isolation of the methyl ester of 15-O-acetylprostaglandin A₂ from *Plexaura homomalla* (esper)

Specimens of *Plexaura homomalla* (esper) were collected in Puerto Rican waters, air dried and stored under a nitrogen atmosphere at 0° C. The cortex was removed, 15 ground and extracted with isomeric hexanes. The organic solvent was evaporated in vacuo to afford a prostaglandin containing residue. The residue was dissolved in nitromethane and extracted with isomeric hexanes. The nitromethane solution was evaporated to give a residue that was approximately 50% by weight of the residue prior to the nitromethane treatment. This process, in addition to the removal of unwanted materials, largely fatty esters, also has the benefit of selectively removing the sterols that have nearly the same Rf. index on silica gel as that of the methyl ester of 15-O-acetylprostaglandin A₂.

Purification of the residue via dry column chromatography using acid washed silica gel and 5% ethyl acetate as elutant yields the 15-O-acetyl-prostaglandin A₂ methyl ester and prostaglandin A₂ methyl ester. The combined yield of the two prostaglandins is 1-2%.

The configuration of the C-15 carbon is established by degradation with ozone followed by chromic acid oxidation to yield α -acetoxyheptanoic acid. The configuration of the acetoxy grouping is established by comparison of the circular dichromism curves of α -acetoxyheptanoic acid and D- α -acetoxypropanoic acid prepared from the calcium salt of D-lactic acid (R-configuration). Compounds of like configuration will display curves of the same sign. D- α -acetoxypropanoic acid displays a negative circular dichromism curve whereas the degradation product, α -acetoxyheptanoic acid gives a positive circular dichromism curve.

What is claimed is:

1. The process of recovering a prostaglandin enriched material, consisting essentially of prostaglandin A₂ 15-O-acetyl methyl ester, 15-epi-prostaglandin A₂ 15-O-acetyl methyl ester, prostaglandin A₂-methyl ester and 15-epi-prostaglandin A₂ methyl ester, from cortex of the gorgonid *Plexaura homomalla* (esper) containing them which comprises the steps of:

(a) digesting dried, comminuted cortex of *Plexaura homomalla* with n-hexane or isomeric hexanes at a

temperature of from about 0° C. to about 60° C. for a period of time sufficient for a substantial degree of extraction of prostaglandin material into hexane to occur;

- (b) removing insoluble solid material from the digested mixture to provide a hexane solution containing prostaglandin material;
- (c) removing hexane from the hexane solution to provide prostaglandin containing material;
- (d) dissolving the prostaglandin containing material in a nitroalkane having one or two carbon atoms or mixtures thereof;
- (e) extracting the nitroalkane solution with a nitroalkane-immiscible solvent selected from the group consisting of alkanes having from six to eight carbon atoms, cycloalkanes having from five to seven carbon atoms, and mixtures thereof at a temperature of from about 0° C. to about 60° C. for a period of time sufficient for a substantial degree of extraction of non-prostaglandin material into the nitroalkane-immiscible solvent phase to occur;
- (f) separating the nitroalkane-immiscible solvent phase from the nitroalkane phase; and
- (g) removing nitroalkane from the nitroalkane phase to provide prostaglandin enriched material.

2. A process in accordance with claim 1 wherein the nitroalkane is nitromethane and the nitroalkane-immiscible solvent is cyclohexane.

3. A process in accordance with claim 1 wherein the nitroalkane is nitromethane and the nitroalkane-immiscible solvent is a mixture of isomeric hexanes.

4. A process in accordance with claim 1 wherein the nitroalkane is nitromethane and the nitroalkane-immiscible solvent is a mixture of isomeric heptanes.

5. A process in accordance with claim 1 wherein the nitroalkane is nitromethane and the nitroalkane-immiscible solvent is a mixture of isomeric octanes.

6. A process in accordance with claim 1 wherein the nitroalkane is nitroethane and the nitroalkane-immiscible solvent is a mixture of isomeric heptanes.
